UNITED STATES PATENT OFFICE

154,440

DESIGN FOR A DRAWING TABLE

Gotthart E. Taubert, Pittsfield, Mass.

Application February 7, 1947, Serial No. 136,765

Term of patent 7 years

(Cl. D33—14)

To all whom it may concern:

Be it known that I, Gotthart E. Taubert, a citizen of the United States, and a resident of 388 Columbus Avenue, city of Pittsfield, Berkshire County, State of Massachusetts, have invented a new, original, and ornamental Design for a Drawing Table, of which the following is a specification, reference being had to the accompanying drawing, forming a part thereof.

On the drawing:

Figure 1 is a perspective view, looking toward one end and the working side of a drawing table, showing my new design.

Figure 2 is a perspective view, looking toward the opposite end and side thereof.

I claim:
The ornamental design for a drawing table, as shown.

GOTTHART E. TAUBERT.
